Specification for Design.

Patented July 6, 1920.

Application filed January 20, 1919. Serial No. 272,207. Term of patent 3½ years.

To all whom it may concern:

Be it known that we, CASSRIEL J. GROSSMAN and SAMUEL M. GROSSMAN, citizens of the United States, residing at Chicago, in the county of Cook and State of Illinois, have invented a new, original, and ornamental Design for Jewelry—Namely, a Ring-Top, Pendants, Cuff-Buttons, Pins, or Articles of Similar Nature, of which the following is a specification, reference being had to the accompanying drawing, forming a part thereof.

In the drawing Figure 1 is a plan view of a ring top, showing our new design.

Fig. 2 is a side view of the ring top.

We claim

The ornamental design for jewelry, namely, a ring top, pendant, a pair of cuff buttons, pin or article of similar nature.

CASSRIEL J. GROSSMAN,
SAMUEL M. GROSSMAN.
